UNITED STATES PATENT OFFICE.

ARTHUR J. THOMPSON, OF FULTON, NEW YORK.

DESIGN FOR A HAMMER.

47,124.

Specification for Design.

Patented Mar. 16, 1915.

Application filed November 28, 1914. Serial No. 874,544. Term of patent 14 years.

To all whom it may concern:

Be it known that I, ARTHUR J. THOMPSON, a citizen of the United States, residing at Fulton, in the county of Oswego and State of New York, have invented a new, original, and ornamental Design for Hammers, of which the following is a specification, reference being had to the accompanying drawing, forming part thereof.

The figure is a perspective view of a hammer, showing my new design.

I claim:

The ornamental design for a hammer, as shown.

ARTHUR J. THOMPSON.

Witnesses:

HUBERT L. GILMAN,
H. D. KEELER.
